UNITED STATES PATENT OFFICE

FRANK S. TRUSLER, OF VERNON, TEXAS

ARTIFICIAL TOOTH

Application filed June 13, 1930. Serial No. 460,985.

This invention relates broadly to artificial teeth, and particularly to the attachment thereof to vulcanite or other dentures for constructing full or partial upper and lower dentures.

It is also comprehended by the present invention to permit of such attaching means being used to advantage in crown and bridge work.

10 Other objects and advantages of the invention will become apparent during a study of the following description taken in connection with the accompanying drawings wherein:—

15 Figure 1 is a vertical sectional view through an artificial tooth, showing one form of my attachment associated therewith.

Fig. 2 is a bottom or inverted view in perspective of the backing plate and pin associated therewith, forming one part of the anchoring or attaching device as shown in Fig. 1.

Fig. 3 is a detail sectional view taken substantially on the line 3—3 of Fig. 1.

25 Fig. 4 is a top plan view of the backing plate.

Fig. 5 is a top plan view of the artificial tooth.

30 Fig. 6 is a perspective view of the tube forming part of the anchoring or attaching means of said one embodiment of the invention.

Fig. 7 is a view somewhat in perspective showing another form of anchoring means, the parts being shown separated.

Fig. 8 is a view similar to Fig. 7 of still another form of anchoring device.

Fig. 9 is a detail view partly in section and 40 partly in elevation with the parts of the anchoring device shown in Fig. 7 arranged in assembled relation.

Fig. 10 is a view taken substantially at right angles to Fig. 9.

45 Fig. 11 is a detail sectional view through

a portion of a denture embodying the features of the present invention.

Fig. 12 is an elevational view of a reinforcing plate forming part of the invention.

With reference more in detail to the drawings, and with reference particularly to Figs. 1 to 6 inclusive, and Fig. 11, it will be seen that numeral 5 designates an artificial tooth provided with a vertical socket 6 opening inwardly from the top face of the tooth. 50

A backing plate 7 formed of any suitable material is adapted to conformably rest on the upper face of the tooth 5, and from the center of the plate 7, there projects a tapered pin 8 adapted to extend into the socket or recess 6. On diametrically opposite sides thereof, adjacent its lower ends, the pin 8 is suitably notched as at 9. 60

Adapted to be arranged in the socket 6 is a metallic tube 10, open at its opposite ends, 65 and it will be seen that the tube tapers longitudinally and on diametrically opposite sides thereof is longitudinally split as at 11 to permit of expansion and contraction of the tube 10 in the socket 6. The tube 10 fits in 70 the upper end portion of the socket 6, and at its lower smallest end, the tube 10 is provided with an outstanding projection or flange 12.

In applying, the anchor or attachment to 75 the tooth, the socket 6 is partially filled with cement or similar substance 13, after which the tube 10 is inserted in the socket and embedded within the cement 13. Next, the pin 8 is passed through the tube 10, so that the 80 plate 7 rests upon the upper face of the tooth 5. Obviously, as the pin 8 passes through the tube 10, the slits 11 which provide for the tube 10 expansible spring fingers is expanded so that the flanges 12 of the tube are pressed into the cement 13. 85

When the pin 8 is passed through the tube 10 as far as possible, it will be seen that the said fingers of the tube 10 will be permitted in view of the notches 9 to slightly contract, 90

so that the flanged lower edge of the tube 10 rests on the shoulder 9' adjacent the lower end of the pin 8, which shoulder as is obvious is formed through the medium of the notches 9.

6 Such arrangement insures a positive and efficient locking connection between the tooth 5 and the plate 7. The plate 7 on the top face thereof is provided with a plurality of up-standing headed studs 14. In securing the 10 tooth 5 provided with my anchoring means to a suitable denture as suggested in Fig. 11, the headed studs are pressed into the lower edge of a vulcanite casing 15, the plate becoming embedded in the casing 15 as suggested.

15 The projections 14 are embedded in the vulcanite casing 15 when the same is in a pliable condition, and obviously, after proper casting and the vulcanite casing becomes partly hardened, the studs 14 will be suitably anchored and embedded within the casing, thus securing the tooth to the casing and providing for a strong denture, capable of withstanding the strain to which it may be subjected.

20 In this connection, it is also to be noted, that 25 embedded within the casing 15 is an elongated plate 16 preferably of flexible material which is adapted to be bent around the front part of the denture. On one face thereof, the plate 16 is provided with a plurality of headed pins 30 or projections 17 which provide an anchorage for a suitable pink gum-like substance forming part of the finished denture, the plate 16 being completely concealed by the application 35 of such gum-like substance.

35 The form of anchoring device as shown in Fig. 7 will be found to be a very useful form of anchoring means for use in securing varied types, or species of tooth, in a denture. In 40 this connection, it will be seen that this form of anchoring device comprises a substantially elongated backing plate 7a having a pin or projection 8a extending from one face thereof. The pin 8a is relatively flat, being somewhat 45 rectangular in cross section. On opposite faces thereof, the pin 8a is provided with notches 9a forming at the lower end of the pin 8 on opposite sides thereof, projections or shoulders 9'.

50 Forming a part of this form of the invention, and corresponding to the tube 10 is an elongated metallic sleeve-like member 10a adapted to be embedded in cement in the socket of a tooth. The member 10a is adapted to receive the pin 8a, and said member 10a tapers vertically from its upper to its lower end to provide inclined side walls. At each end thereof, the member 10a is slit as at 11a so that when the pin 8a is passed through the 55 member 10a, the same will expand so that the flanges 12a on the lower edge of the member 10a will be embedded in the cement in the socket of the tooth.

60 When the parts are in assembled relation 65 for anchoring the tooth to a denture, it is ap-

parent that the flanged ends 12a will also rest on the shoulders 9' in the same manner as the flange 12 rests on the shoulders 9' in the first referred to embodiment of the invention. Such an arrangement is clearly suggested in Fig. 9, and Fig. 10.

65 Fig. 8 illustrates still another form of the invention. In this form of the invention, it will be seen that I also provide a pair of complementary members, one of which includes a 70 face plate 7b having a rounded tapered pin 8b projecting from one face thereof. At its smallest or free end, the pin 8b is provided with a disk-like head 18.

75 For cooperation with the pin 8b is an elongated tapered tube 10b which like tube 10 is slit on diametrically opposite sides thereof to provide expansible spring fingers. The slits being designated by reference characters 11b.

80 Likewise the tube 10b at its lower end is provided with an outstanding flange 12b, which when the parts are in engagement, one with the other, will rest on the upper face of the head 18 of the pin 8b. Obviously as the 85 pin 8b is passed through the sleeve 10b, the head 18 will act to expand the tube 10b in the same manner as the shoulder 9' acts to expand the tube 10.

90 By using this method of anchorage as suggested in either form of the invention, it will be found that the socket 6 in the tooth may not be so deep or extend so far into the porcelain which heretofore has been the case, resulting in the weakening of the tooth. 95

100 Furthermore, such an anchoring means as comprehended by the present invention will eliminate all possibility of the pin of the anchoring member projecting through the porcelain of the tooth onto the occlusal surface which of course, makes for a bad appearance, and in addition, the fluid of the mouth would tend to dissolve the cement from around the pin, thus weakening the connection around the tooth which would be 105 liable to work free of the anchor.

110 Furthermore, it will be appreciated that an anchoring means of this character which permits of the socket in the tooth terminating inwardly at its closed end of the tooth, makes 115 for a much stronger and sanitary denture.

120 Even though I have herein shown and described the preferred embodiment of my invention, it is to be understood that the same is susceptible to changes fully comprehended by the spirit of the invention as herein described, and the scope of the appended claim.

125 Having thus described my invention, what I claim as new is:—

In an artificial denture, a tooth having a 125 socket opening inwardly from one face thereof, a backing plate adapted to be secured to the tooth, a pin projecting from said backing plate, a tube arranged in the socket of said tooth, said pin adapted to extend into said 130

socket thru said tube, shoulders formed on said pin adjacent the free end of the pin for engaging the inner edge of said tube, said tube at said inner end being slit, said pin adapted to expand said tube in said socket when said pin is passed through said tube, cement in said socket about said tube, and said tube at said inner end provided with outstanding flanges adapted to be embedded in the cement upon expansion of said tube.

10 In testimony whereof I affix my signature.
FRANK S. TRUSLER.
